UNITED STATES PATENT OFFICE.

HAROLD M. PLAISTED, OF ST. LOUIS, MISSOURI.

PNEUMATIC SEPARATOR.

1,311,358.

Specification of Letters Patent.

Patented July 29, 1919.

Application filed February 17, 1919. Serial No. 277,623.

To all whom it may concern:

Be it known that I, HAROLD M. PLAISTED, a citizen of the United States, residing at St. Louis, Missouri, have invented certain new and useful Improvements in Pneumatic Separators, of which the following is a specification.

This invention relates to certain new and useful improvements in pneumatic separators the peculiarities of which will be hereinafter described and claimed.

The main object of my invention is the provision of means for producing a centrifugal action in an inclosed stream of particle-laden air traveling at substantially uniform linear velocity in a conduit of substantially uniform cross sectional area, and thus effecting a condensation of the particles at the outer side of the stream; and then skimming off successive layers of the condensed side of said stream and collecting the graded particles. Another object is the regulation of the linear velocity and quantity of air, according to the weight and size of the said particles, and thereby determining the velocity and quantity of air required to convey particles of different material respectively.

In the accompanying drawing on which like reference letters indicate corresponding parts, Figure 1 represents a plan view, partly in section, of a device exemplifying my improvements; Fig. 2 a vertical section of the same on the line 2—2 of Fig. 1; Fig. 3 a detailed plan section of a tailings valve with skimming wing; Fig. 4 another detail view of a tailings valve of modified form; Fig. 5 a similar detail view of a tailings valve in the form of a hinged door acting as a skimmer; Fig. 6 a vertical sectional view of the valve shown in Fig. 3 with adjacent parts; and Fig. 7 an elevation of a grinding and separating system with my improved pneumatic separator applied thereto.

In other forms of pneumatic separators the particle-laden air is drawn by suction, or driven by blast, into a chamber of larger diameter than the pipe leading thereto, whereby the velocity of the air is suddenly decreased by the expansion due to entering the chamber, and the material particles carried by the air are dropped to a large extent, while the partly purified air with the finer particles therein, passes out of said chamber to a collector for the finer particles. This style of separator attains its effect by

a sudden loosening of its hold upon the particles carried by the air, and the air is then picked up again by the suction, or is again forced onward when a blast system is used, in order to carry the finer particles out to their final collection or separation.

In my system however a continuous current of air is produced either by suction or by blast, in a conduit of practically uniform cross sectional area, which conduit is formed, in the preferred construction, in a flat horizontal spiral about a vertical axis. One end of the conduit, such as the outer end of the spiral, serves as the inlet for the air, and the other end of the spiral serves as the outlet for the air and finest particles that have not been deposited in compartments connected to regulated openings in the side walls of the conduit, or in the bottom of the conduit, at definite periods throughout its length. By the spiral form of conduit and the uniform size of the same, the material that is fed into the conduit near the inlet opening for the air, is carried around with uniform linear velocity, but with increasing angular velocity as the stream approaches the center or outlet of the spiral. By this centrifugal action on the particles carried by the stream of air, the particles are condensed along the outer side wall of the conduit continuously, and tend to pass outward through openings in said wall into compartments connected therewith. As the velocity of the air necessary to carry comminuted material of the kind generally ground and pulverized is much greater than that due to gravity, the particles will tend to hug the outer side wall of the conduit in greater condensation than along the bottom of the conduit. I have therefore provided the larger number of openings for the escape of tailings in the side walls of the conduit; and since the particles are of different size I have provided means for varying the size of the tailings openings for more readily controlling the grade and uniformity of the tailings passing through said openings.

While my improved separator may also be used in connection with a blast system or with air under pressure, I prefer to use it with an exhaust system or with air under suction and will now describe it in connection with such a system. The letter A designates an exhaust fan, such as a fan carried by the shaft of a mill B having a driving

pulley C. The fan delivers in the direction of the arrow through a pipe D to a cyclone collector E from which the air escapes through a pipe F and the finer particles are collected in a collector G of any well known type. The bottom of the cyclone collector is provided with a rotary valve H for the material deposited in the collector E.

A pipe I is connected to the suction side of the said fan A and leads to the outlet J of a spiral separator of improved form comprising horizontal top wall K and bottom wall L forming parallel planes, between which is formed a continuous spiral conduit by means of a vertical wall, preferably double, and curved horizontally about a vertical axis, and extending from the outer end of the spiral conduit M in curves of decreasing radii, to the inner end or outlet of the spirals before mentioned. Near the inlet for the air, and preferably in the top wall of the conduit, is located a feed hopper N having a wheel O by which regulated quantities of the material ground by the crusher B, is fed from a storage hopper P, down upon a screen Q inclined downward in the direction of the air current, so as to allow the current to pick up and carry onward the material delivered through a feed opening q.

A practical form of construction is to make the top and bottom walls of the separator of wood, matched and joined, and stiffened by angle iron, as indicated in Figs. 1 and 2. One wall, preferably the bottom, is grooved at 9 to receive the vertical walls before mentioned, and when such walls forming the sides of the conduit are doubled as shown in the preferred form in Fig. 1, the intermediate space between the continuous wall R and the tailings wall S, is provided with filler blocks T that also serve as stops or partitions across said intermediate space, between the tailings openings in said wall S. The connecting bolts through top and bottom walls pass between said walls R and S and thus present no obstruction to the stream of air in the conduit passage. The bottom wall is preferably grooved, as shown in Fig. 2, for both of said vertical walls R and S, and a layer of felt k is interposed between the lower side of the top wall and the upper edges of the said walls R and S, to effect practically air tight contact between the same.

I designate the tailings openings in said wall S by the letter U, and in each opening is mounted a valve or regulating device to vary the size of said opening,—such as a vertical pipe V passing downward through the bottom wall into a compartment 10 provided with a slide, but air tight in normal condition and adapted to receive the tailings passing through said pipe V, or other inlet thereto. The upper part of the said pipe is preferably provided with a closing disk W,

and central pin X passing through the upper wall and having a crank arm Y secured thereto for turning said pipe. A pin 3 or other means acts as a stop for the arm Y, and a packing washer 4 prevents the entrance of air around the central pin X. Below the disk W is an opening 5 in the pipe extending to the bottom wall, which opening is preferably provided with a wing 6 that extends out through the opening U into the conduit space, a more or less distance according to the rotation of the pipe V. When the wing is rotated to make contact with the wall S by its outer edge, the opening U is closed. The normal position however is with the wing extending into the conduit passage as shown in Fig. 1, and varied according to the material being separated. By practical use I have found that the openings U should be less in size near the beginning of the spiral, and that the opening may be increased in size by adjusting the valves or otherwise as we approach the center of the spiral. In some material containing relatively heavy particles I prefer to use the form of the valve shown in Fig. 4 in which the wing 6' is directed inward,—that is, in the intermediate space between the walls R and S,—instead of outward into the conduit as in Fig. 3. The bottom wall has an opening V' corresponding to the pipe V and communicating with the closed compartment 10 below the separator. The wing 6' Fig. 4, closes the opening U by swinging like a door upon the pivot pin X', which may extend through the upper wall and have a lever arm or crank to turn it in the same way as the center pivot pin of Fig. 6.

Fig. 5 shows this form 6' with the hinge at the farther side of the wing and with the wing itself projecting into the passage to act as a skimmer in the same way as the wing 6 of the pipe V.

While all the particles in the moving stream of air are subject to centrifugal action, the heaviest particles or those of heavy material, will be more influenced by gravity than particles of a light material and smaller size. For this heavy material or heavy particles, I provide tailings openings V² in the bottom wall and adjacent to the inner wall S, and provided with any suitable form of adjustable valve, preferably the one shown in Fig. 5 with the wing 6² extending upward when open, and closing the opening in the bottom when depressed by a handle Y' Fig. 6.

In the pipe I connecting the fan with the outlet to the separator, I provide an air inlet valve 8, by opening which the suction through the separator is reduced accordingly. In handling fine and light material, the velocity of the air and quantity of the air passing through the separator, may thus be varied to correspond with the material

being handled. In a full size construction of this separator I have found that pulverized bituminous coal weighing 39 lbs. per cubic foot and 67% passing 150 mesh 5 can be handled with an air velocity of 3800 feet per minute. On the other hand barytes weighing 136 lbs. per cubic foot of a grade of 60% passing 350 mesh requires the full power of the exhaust fan, which 10 in this case gave 4500 feet per minute in velocity of the air passing through the separator. It was also found that a finely pulverized earth weighing 27 lbs. per cubic foot and of over 99%—350 mesh, would be carried through with a larger opening of the air valve 8 and a corresponding decrease of velocity and quantity of air required to handle it through the separator. By this 15 separator and air regulating valve, I am able to determine the velocity and quantity of air required to move any material in particles in a stream of air as a vehicle, as well as to separate any desired grade of said 20 particles from the air in said stream.

25 I claim:

1. A pneumatic separator comprising horizontal top and bottom walls having outlets, an interposed partition forming a continuous spiral passage of unobstructed cross 30 sectional area for particle-laden air current,—said partition consisting of an imperforate outer wall and an inner wall having tailings outlets, and valves mounted between said partition walls and forming 35 regulatable passages from said tailings outlets in said partition to said outlets in said bottom wall, substantially as described.

2. A pneumatic separator comprising a top

wall, a bottom wall having tailings outlet openings, an interposed partition constituting a continuous passage under air suction from its inlet to its outlet for carrying particle-laden air,—said partition consisting of an outer imperforate wall, and an inner wall having tailings outlet openings 40 and forming a dead air space between them, and air tight compartments located below said bottom and communicating with said tailings outlets under air suction, substantially as described.

3. A pneumatic separator comprising a top, bottom and interposed partition walls forming a continuous passage for particle-laden air currents,—said bottom wall and partition having adjacent tailings outlets,— 45 rotatable pipes mounted in said tailings outlets and each having a slot above said bottom wall provided with a lateral wing projecting into said passage and more or less closing the outlet in the partition wall, substantially as and for the purpose described.

4. In a pneumatic separating system the combination with walls forming a conduit for particle-laden air, and having tailings outlets, and adjacent closed compartments, 65 an adjustable valve mounted in each tailings outlet and consisting of a rotatable pipe communicating with said compartment and having a lateral opening provided with a skimming wing, and having a central 70 pivot and a crank lever outside said conduit for rotating said pipe.

In testimony whereof I have affixed my signature.

HAROLD M. PLAISTED.
